UNITED STATES PATENT OFFICE.

FRANK G. DEAN, OF PHILADELPHIA, AND GEORGE M. KENDALL, OF MELROSE, PENNSYLVANIA; SAID KENDALL ASSIGNOR TO SAID DEAN.

GAS OR VAPOR STOVE.

SPECIFICATION forming part of Letters Patent No. 792,502, dated June 13, 1905.

Application filed January 21, 1905. Serial No. 242,131.

To all whom it may concern:

Be it known that we, FRANK G. DEAN, a resident of Philadelphia, and GEORGE M. KENDALL, a resident of Melrose, Montgomery county, Pennsylvania, citizens of the United States, have invented certain Improvements in Gas or Vapor Stoves, of which the following is a specification.

The object of our invention is to provide a gas or vapor stove or range with means whereby the heat from a single burner can be economized, controlled, and distributed in such manner as to provide for the effective heating of two or more cooking utensils, one of which may, if desired, be subjected to a higher degree of heat than the other or others.

When the device constituting the subject of our invention is in the form of an attachment, it is by preference interchangeable with either of the plates or gratings with which a gas or vapor stove or range is usually provided, or all of said plates or gratings may be thus replaced, if desired. Hence the advantages of our invention may be attained without any change in the structure of the stove or range itself.

In the accompanying drawings, Figure 1 is a perspective view of sufficient of an ordinary gas stove or range to illustrate the application of our invention thereto. Fig. 2 is a longitudinal section of the same, and Figs. 3 and 4 are sectional views illustrating a modification of the invention.

1 represents the top of an ordinary stove or range intended for the use of manufactured or artificial gas, 2 representing the burners of the stove, 3 one of the usual gratings of the same, 4 the extension-shelves at each end of the stove, 5 the gas-supplying pipe, and 6 the cocks whereby the flow of gas to the various burners is regulated. Usually the top of a stove or range of this character is grated throughout. Hence there is no means for economizing or controlling the distribution of the heat of the various burners, which heat is applied only to a cooking utensil or utensils placed above the burner. Attempts to distribute the heat have been made by the use

of special structures mounted above the top of the stove or range; but no such attempts, so far as we are aware, have been successful in the attainment of the object sought, one reason for such failure being that such structures so change the vertical relation of the cooking vessels to the burners that the heat of the latter cannot be utilized to the best effect.

In carrying out our invention we replace one or we may replace each of the usual gratings 3 with an imperforate plate 7, which is fitted to the top of the stove in the same manner as the grating which it displaces, the top surface of this plate being by preference level with the tops of the bars of the grated section when but one of the latter is displaced, so that a cooking utensil can be readily moved from one to the other. In this plate are formed pot holes or openings, one above each of the corresponding burners of the stove, these pot-holes being provided with cover-plates 8, and each cover-plate has by preference a smaller pot-hole provided with a cover-plate 9.

In the present instance we have shown our invention as applied to a range in which the cover-plate extends transversely over the two front burners; but, as will be evident, the cover-plate may extend across the back instead of across the front, or it may extend from front to rear instead of transversely, and it may be applied to a range having three or more burners abreast or in line fore and aft.

To the under side of the plate 7 is secured a flue structure or casing 10, which extends from end to end of the plate and has at one end a depending flange or collar 11, surrounding one of the burners 2 of the range, the under side of the casing also having above the other burner 2 an opening provided with a removable cover-plate 12, as shown in Fig. 2.

At that end of the casing 10 which is farthest from the depending flange or collar 11 are openings provided with a movable damper 13, so that they can be opened or closed, and adjacent to one of the pot-holes at the corresponding end of the plate 7 are a series of openings 14, as shown in Fig. 1. By reason

of this construction the hot air and products of combustion arising from the burner 2 through the collar 11, after acting upon the bottom of a cooking utensil placed over the 5 pot-hole above said burner, are deflected laterally through the flue structure and act upon a cooking utensil placed over the pot-hole above the other burner 2, escaping finally through the openings 14 and also through the 10 openings 13, if the damper controlling the latter is open. Hence a single burner is available for heating two or more cooking utensils and the heat is utilized to much better advantage than in an ordinary gas or vapor stove 15 or range. For instance, the vessel directly above the burner may receive the full heat of the flame from the burner, as in an ordinary stove, while the other vessel may be heated to a lesser degree, so as to simply simmer its 20 contents or keep them warm.

The heat to which either cooking utensil is subjected may be tempered by the use of the pot-hole covers in the same manner as in an ordinary coal stove or range, a maximum heating being effected by removing both of the 25 covers 8 and 9, an intermediate degree of heat being obtained by removing the cover 9 only, or a minimum degree of heat resulting if neither cover is removed. In order to increase 30 the amount of air to support combustion, the sides of the casing 10 may be provided with openings 15, as shown in Fig. 2.

If it is advisable to utilize the full effect of 35 the heating property of each of the burners 2, the cover-plate 12 may be removed and both burners may be lighted, and where the attachment is thus constructed it may be advisable to extend the openings 15 around all sides of the casing 10.

40 Instead of providing the pot-hole which is remote from the burner with a closed cover 8 we prefer in some cases to use in connection with the same a grated cover 16, Figs. 3 and 4, the bars forming the grate of said cover 45 projecting above the rim on one side, but being flush with the rim on the other side. When, therefore, this cover is used with the projecting bars uppermost, as in Fig. 3, a space is afforded for the escape of the heat beneath the 50 bottom of the cooking utensil as well as through the other openings provided; but when the cover is used with the flush sides of the bars uppermost, as shown in Fig. 4, flat-irons or other objects can be readily moved 55 onto or off of the same.

We are aware that stoves or ranges intended for the use of natural gas have been constructed with closed tops having pot-holes provided with covers; but no such top plates, so far as 60 we are aware, have been provided with flue structures beneath the same, such as that which we have provided.

In applying our invention to a natural-gas stove or range the top of the plate 7 will be

flush with the top of the range instead of being raised above the level of the same, as when used in connection with a grated cover, or we may, if desired, apply our improved flue structure to the ordinary top plate of such a stove or range. In an ordinary natural-gas range 70 all waste products of combustion are directed to an outlet communicating with a discharge flue or chimney, and in applying our invention to such a range the escaping products of combustion from the flue structure would of 75 course be directed to such general outlet.

It will be evident that our invention is applicable to what are termed "hot plates" as well as to stoves or ranges. Hence we intend the term "stove" as used in our claims to 80 cover all gas or vapor heated devices of this character.

Having thus described our invention, we claim and desire to secure by Letters Patent—

1. A gas or vapor stove having an inclosed 85 flue structure below the top of the stove for collecting and laterally distributing the heat from a burner, whereby such heat is conveyed to a cooking utensil placed alongside of said burner, substantially as specified.

2. An attachment for gas or vapor stoves, consisting of a plate interchangeable with an ordinary top plate of the stove, and having a flue structure on the under side of the same for collecting and laterally distributing the 95 heat from a burner thereof, substantially as specified.

3. A gas or vapor stove having an inclosed and laterally-extending flue located beneath 100 the top plate of the stove and having a depending flange or collar, which surrounds one of the burners, substantially as specified.

4. A gas or vapor stove having an inclosed flue structure which receives the hot air and 105 products of combustion from one of the burners of the stove, and has, at a point remote therefrom a dampered escape-opening, substantially as specified.

5. An attachment for gas or vapor stoves, consisting of an inclosed flue structure which 110 receives the hot air and products of combustion from one of the burners of the stove and is located below the top plate of the stove, one of the elements of said flue structure being a top plate having pot-holes side by side, one 115 above said burner and the other alongside of the same, substantially as specified.

6. An attachment for gas or vapor stoves, consisting of an inclosed flue structure which 120 receives the hot air and products of combustion from one of the burners of the stove, one of the elements of said structure being a top plate having pot-holes and openings independent thereof and remote from said burner for the escape of said hot air and products of 125 combustion, substantially as specified.

7. A gas or vapor stove having a flue structure extending over a plurality of burners of

the stove, and having a normally open inlet for the products of combustion from one of said burners, and an inlet with removable cover-plate for each of the other burners, substantially as specified.

8. The combination in a gas or vapor stove, of a grated top plate, and a flue structure for receiving, collecting, and distributing the products of combustion from a burner of the stove, one of the elements of said flue structure being a top plate which is flush with the

tops of the bars of the grating, substantially as specified.

In testimony whereof we have signed our names to this specification in the presence of 15 two subscribing witnesses.
